MACHINE FOR FINISHING SURFACES

Robert S. Drummond, Detroit, Mich., assignor to
National Broach & Machine Company, Detroit,
Mich., a corporation of Michigan

Original application February 8, 1937, Serial No.
124,790. Divided and this application October
11, 1937, Serial No. 168,509

16 Claims. (CL 90—15)

The invention relates to apparatus for finishing round or flat surfaces, and more particularly it relates to a new art of removing metal from such surfaces which, in its accuracy of finishing, 5 resembles more nearly the art of grinding, but which nevertheless is distinctly a cutting or shaving operation resulting in the removal of fine chips or shavings from the surfaces. This application is a division of my pending application 10 for patent Serial No. 124,790, filed February 8, 1937.

The invention in its broader aspects has many and varied uses, and this application is directed to the invention in its broadest sense. On the 15 other hand, the application is also directed to certain specific embodiments of the invention and therefore in the description hereinafter given, reference will be made particularly to a method and apparatus for finishing flat and 20 cylindrical surfaces such as will be found, for example, on axle shafts for motor vehicles.

An object of the invention is to provide a rotary cutting tool capable of removing extremely fine shavings from metal surfaces and which is oper- 25 able at pressure greatly less than that for cutters now employed for finishing surfaces.

A further object is to provide a machine adapted for rapid and accurate finishing of round and flat surfaces.

30 A more specific object of the invention is to develop a machine and suitable cutting tools therefor which are adapted for the simultaneous finishing of adjacent round and flat surfaces.

These and other objects are accomplished by 35 the apparatus hereinafter more fully described, and illustrated in the accompanying drawings, wherein

Fig. 1 is a plan view of a machine embodying my invention;

Fig. 20 is a diagram showing the method of obtaining a uniform cylindrical surface when the axes of the tool and the cutter are crossed. 20

In the drawings, the base of the machine is indicated at 10. Adjustably mounted on the base on suitable guideways shown at 11 in Figs. 2 and 3, are a tail stock 12 and tool carriages 13 and 14. Each carriage is adjustable on a guide 15, the initial adjustment being made by means of setting wheels 16, 17. The tail stock is set by manipulation of handle 18, the work being held by the tail stock and a center 19 on the base. As shown in Fig. 1, the particular type of work to be finished is an axle 20 having a cylindrical bearing surface 21 and a bevel gear 22 formed integral with the axis, the back face 23 of the gear and the surface 21 being those surfaces which are to be finished. 30

Each of the carriages 13, 14, and its guideway is angularly disposed to the axis of the axle to be finished. On each carriage there is journaled a cutting tool indicated at 24, 25. The axis of each cutter is disposed at a right angle to its particular guideway, and the cutter has a cutting face angularly disposed to the axis of the tool. In Fig. 1 it will be seen that the tool resembles a bevel gear having spiral teeth thereon. The angle of the cutting face is such that when the tool is moved into cutting relation with the work, it will be parallel to the surface to be finished. 40

In the drawings are shown four motors, all indicated by the numeral 26, one for each of the tools, another for rotating the work, and still another for operating means to reciprocate the tools toward and from the work. Connecting the motors and their respective driven members are belts or chains 27 and suitable speed reduction 50

55

mechanism 28. Initially, the tools are set on guides 15 to make a definite plunge cut in the surfaces to be finished. The means for subsequently moving the tools towards and from the work include a cam 29 fixed with relation to worm wheel 30, the latter being rotated by worm 31 forming part of the reduction mechanism between the cam and its driving motor. Each of the guides 15 is connected to one link 32 of a toggle mechanism 33, the other link 34 of which is pivoted to link 32 at 35. The pivot 35 is movable in an arcuate path about shaft 36, having means thereon for rocking the toggle. The axis of shaft 36 is fixed with relation to the base 15 of the machine. It will thus be seen that the connection between link 32 and guide 15 is movable towards or from shaft 36 as the toggle is straightened or bent.

The means for rocking shafts 36 include an arm 37 keyed to each shaft and a connecting link 38, the ends of which are pivotally connected to arms 37. Mounted on link 38 is a roller 39 adapted to cooperate with an elongated opening 40 in one end of lever 41, the latter being pivoted intermediate its ends to the base at 42. At the other end of the lever is a cam follower 43 cooperating with cam 29. It will be seen that cam 29 is provided on its peripheral face with a low portion 44 permitting follower 43 to move radially toward the center of the cam whereupon roller 39, link 38 and arms 37 are moved. This results in a bending of the toggles, which in turn simultaneously move the carriages and the tools carried thereby away from the work. This movement may be effected by suitable spring mechanism or a track cam if desired. Also, suitable automatic limit switches for stopping the motor while the machine is being loaded and unloaded are provided.

40 The arrangement of the carriages and crossed axes just described obviously permits the advance of tools of relatively small diameter towards and into cutting relation with the work, although their driving mechanisms may be somewhat larger than the tool itself. Also, the pressure angle of the cutting face permits shaving of the surface with less compression of the metal. Because the driving means for the tool and work are independent of each other, it is possible to 45 regulate the cutting actions of the tools and thus insure the most efficient operating conditions for finishing two surfaces, like or unlike, simultaneously.

In Figure 1, it will be noted that the cutting tool 24 is used for finishing the round surface 21, and the cutting tool 25 is used for finishing the flat surface 23. Figure 5 shows an enlarged perspective view of the cutter 24. While my invention in its broader aspects contemplates cutters 50 of various types, I will first specifically describe one form of cutter which has proven very satisfactory for commercial production in the finishing of axle shafts. The cutter 24 has spiral teeth 50 formed in the beveled face of the tool 55 and, as shown, the teeth are disposed in the form of a left-hand spiral. In the particular cutter illustrated, the distance between adjacent teeth in normal section is .160 of an inch. The tops 51 of the teeth have a width of $\frac{3}{16}$ of an inch and are backed off or relieved at a suitable angle α , such as 2° . Intermediate adjacent teeth are recesses 53 of a suitable width and depth to carry away the shavings, and, as shown, this depth is $\frac{3}{32}$ of an inch. The recesses are so 60 shaped as to provide a suitable rake on the front

face 54, such as a rake angle β of 5° . The cutter as shown has an outside diameter of $6\frac{1}{8}$ inches and a face width of 1 inch. The tool 24 is designed to operate in the shaving of the round surface 21, the diameter of which is $1\frac{1}{4}$ inches.

The other cutter 25 is constructed to shave the flat surface surface 23, which is an annular surface extending radially outward from the round surface 21. The face extends to the outer diameter of the gear 22 which is $2\frac{7}{8}$ inches in diameter. The cutting tool 25 is constructed in the same manner as the cutting tool 24, but the teeth are in the form of a right-hand spiral instead of a left-hand spiral.

It is important that the relative rotations of the cutting tools and the axle be properly determined, and one relationship which has proven satisfactory in this specific case is to rotate the axle 20 at 425 R. P. M., the cutter 24 at 125 R. P. M., and the cutter 25 at 250 R. P. M. The direction of rotation is also important, since it is desired that the movement of the work surface past the cutting tool should be against the spiral angle of the tool. The directions of rotation are indicated in Figure 1, the arrow 55 indicating the direction of rotation of the axle 20, and the arrows 56 and 57 illustrating respectively the rotation of the cutters 24 and 25.

With the cutting tools and speeds as above described, it has been found that both the round and flat surfaces to be finished can be finished very accurately by the plunge cutting previously described. The direction of feed of the cutters 24 and 25 during the plunge cut is inward along the axes of carriages 13 and 14 respectively, at a small angle to the surface of the work. For the finishing of these surfaces to a desired stand, it ordinarily requires the removal of .012 of an inch on each side of the round diameter 21, and the removal of .020 of an inch from the flat surface 23.

It is to be understood that the specific data with respect to the cutting tools, rotations, feeds, etc., have been given above merely by way of example and is capable of considerable modification. However, to obtain good shaving action, it is necessary that the various factors, described above, be definitely correlated, and the example has been cited to show one suitable way for obtaining these results.

In the machine as illustrated in Figure 1, the shaving action is effected by plunge cutting only, but the invention is also capable of embodiment in other modified methods. For example, it may be desirable to introduce a slight oscillation or single cross feed at the end of the plunge cutting cycle in a direction parallel to the surface to be finished. Such an additional movement has the tendency to improve the surface finish by "cleaning up" the slight imperfections or tool marks which may be left by the plunge cut operation. This is diagrammatically illustrated in Figure 7. The cutter 25 is given an oscillation indicated by the arrow 60 parallel to the surface 23, and the cutter 24 is given an oscillation indicated by the arrow 61 parallel to the axis of the shaft. This oscillation is preferably imparted only at the conclusion of the plunge cutting stroke and is ordinarily of relatively small amplitude, since this is sufficient for cleaning up the surface. For example, a feed of only $\frac{1}{8}$ of an inch is ordinarily sufficient. However, if desired, the oscillation may be simultaneous with the infeed due to the plunge cutting.

In the finishing of cylindrical surfaces as

shown in Figure 1, the axes of the cutter 24 and the axle 20 lie in the same plane. The relationship of the parts is shown in the diagrams, Figures 8 and 9, where 62 is the axis of the cutter 24 and 63 is the axis of the round work piece 21. In Figure 9 both axes appear to be coincident.

The invention also contemplates the finishing of round surfaces where the axes of the work and cutter do not lie in the same plane but are crossed at a limited angle. This is diagrammatically illustrated in Figures 10 and 11 where 65 represents the axis of the cylindrical work piece 66, and 67 is the axis of the cutter 68. When the axes are crossed as illustrated, the zone of contact instead of extending across the face width of the cutter as in Figure 8, would extend only for a limited distance on each side of the center 69 of crossed axes. In other words, at the points 70 and 71 there would normally be a certain amount of clearance or backlash due to the crossed axes relationship. In order to compensate for this backlash, the double cutter 68 has its surface hollowed or dished as indicated by the line 72, and by properly proportioning the amount hollowed out, the cutter can be provided with a surface which will cut uniformly over the entire face width of the cutter.

It should be understood that if it is desired to shave a cylindrical surface 66 for a greater axial distance than the width of the cutter 68, a feed movement can be given parallel to the axis of the work. It should also be understood that where a cutter is not dished but has a straight bevel surface, the finishing action along the surface of the cylindrical work 66 may be obtained by a feed movement in the direction of the axis of the work, or other direction as explained in Figure 20.

A modified form of rotary cutting tool is shown in Fig. 12. This cutter 73 is generally similar to the cutter 24 shown in Fig. 5, except that the teeth 75 are inclined at a greater helical angle and now resemble worm threads. In the construction illustrated, there are eight threads, 45 each having a lead equal to the width of the cutter, which is in this case approximately 1 inch. As shown, the width of the lands 76 is approximately equal to the width of the gashes 77, and the depth of each gash is equal to its width. These dimensions of course may be varied under different working conditions. It has been found that excellent results may be obtained working with tools having the widths of their teeth and recesses and the approximate depth of 50 the recesses all .060 of an inch. In some instances it may be desirable to provide shallow concave grooves 78 in the faces of the lands, thereby to reduce the contact surface of the tool on the work. Regardless of whether the lands 55 are straight or grooved, it is apparent that a plurality of closely spaced cutting edges operate simultaneously on the work. Since these lands are disposed angularly to the line of contact between the work and the tool, the point at which 60 the cutting edge engages the work constantly shifts upon rotation of the tool or the work, or a combined rotation of the work and the tool. The rotation of the tools and the work is so timed that the cutting speed can be regulated 65 to obtain the best cutting results.

Obviously the faces of the lands act as limiting gauges and, depending on the pressure on which the tool is forced against the work, the depth of the cut can be controlled to shave the work 70 to a minimum hitherto impossible with the known

types of cutting tools. Since the ordinary pressures necessary to cut with the present method are much reduced, the heating of the work due to the cutting action is reduced to a minimum. It has been found in practice that the shavings and chips are not discolored as is the case when cuts of several thousandths of an inch are taken, most tools having to dig into the metal to such an extent that the metal removed shows unmistakable signs of having reached relatively high 10 temperatures during the cutting operation. This objectionable heat effect is entirely absent in the present invention.

While the invention has been described as one applicable to the finishing of surfaces on rotating 15 work pieces, it is not intended that it be limited to the specific embodiment illustrated. And while the operation has been described as a plunge cut, i. e., with no reciprocation of the tool or work during the cutting operation, it is obvious 20 that means for moving either the work or the tools, or both, to effect relative axial movement thereof, may be employed. Under some circumstances it may be found desirable to gear the work and tools, in which case a single drive 25 motor is contemplated, but for flexibility and variety of operations, it has been found expedient to employ independent drives.

Referring again to Figure 1 which shows rotary cutters operating on both round and flat surfaces, 30 it is desired to point out that by reason of the arrangement of the cutting edges on the tools, together with the fact that both the tools and the work are simultaneously rotated, an entirely novel type of cutting action takes place. The 35 chips made by these tools are slivers, and unlike chips from milling cutters or other machine tools which are normally used for finishing surfaces. The chips from the cutting tools of my invention have more the appearance of lathe chips and 40 are not upset as much as the chips from milling cutters. This may be explained from the fact that the teeth on the cutter cut more nearly around the work piece in a generally circular direction and do not cut straight across the piece, 45 even though the cutting edges of the teeth contact at points lying in a straight line. Generally speaking, the cutting edges cut the work piece along lines which are transverse to the axis of the work and extend at an angle between 10° 50 and 80°. Thus the cutting edges take long chips from the surface by cutting in a thread-like path, but finish a uniform surface shape whether this be a flat surface or a round surface.

In Figure 13 I have shown a modified method 55 of finishing a round surface to the specified dimensions. In this figure, 80 represents the cylindrical work piece and 81 the cutter. Instead of plunge feeding as shown in Figure 1, I provide a cross feed of the cutter relative to the work 60 in the direction of the arrow 82. Thus the cutter is first offset laterally with respect to the work and is fed toward the work for a distance 65 sufficient to give the specified depth of cut, and the cutter is then fed in the direction of the arrow 82. This finishes the cylindrical surface 70 completely to a predetermined size. If it is desired to reduce the size still further, the cutter may be again fed toward the work and again caused to traverse in the direction of the arrow 75 82, or in the opposite direction.

Figures 14 and 15 further illustrate methods 80 of finishing round surfaces in accordance with my invention. In this case, the cylindrical work piece 84 is acted upon by the beveled rotary cutter 75

65, and the arrows 86 and 87 indicate alternative methods of infeeding toward the work. Arrow 88 shows the infeed in a plane transverse to the axis of the cylindrical work piece 84, while arrow 89 shows the feed in a plane transverse to the axis of the rotary cutter 85. Either of these infeeding motions may be combined with a cross-feed as indicated by the arrow 88. Again the cross-feed may be in the reverse direction as indicated by the arrow 89.

10 In Figure 16 I have indicated a method for finishing cylindrical surfaces having a corner radius, or fillet, 90 adjacent the cylindrical surface 91. In this case, the beveled cutter 92 has the 15 beveled surface 93 rounded as at 94 to correspond in shape to the corner radius 90. The teeth 95 in this cutter are formed, as in the previously described cutters, by a series of grooves 96 extending helically. These grooves must be of 20 sufficient depth at the rounded corner 94 so that the tops of the lands intermediate the grooves when rounded will still leave sufficient depth of groove to form the cutting edges.

25 Figure 17 illustrates a further method of finishing cylindrical surfaces slightly modified from that illustrated in Figure 1. The cylindrical surface 21 is acted upon by the beveled face of the cutter 24. The surface may be completely finished by means of a plunge cut toward the work 30 in the direction indicated by the arrow 97 which is in a plane perpendicular to the axis cylindrical to the work. However, the direction of feed of the plunge cut may be along some inclined line as indicated by the arrow 98, in which 35 case it is only necessary that the beveled surface 99 of the cutter be of sufficient width to contact with the entire active surface of the work 21, both at the beginning and the end of the plunge cut.

40 A further modification of this method is indicated in Figure 18 where, instead of having merely a plunge cut as indicated by the arrows 97 and 98, there may also be combined a single cross-feed in the direction of the arrow 100. 45 Similarly, the plunge feeds 97, or 98, may be combined with the cross-feed 101 in the direction opposite to the arrow 100.

50 In describing the various forms of cutters which may be used, I have referred usually to the fact that the grooves forming the cutting edges extend in a helical path. However, in some instances, it may be desirable to have these grooves radial as indicated in Figure 19. In this figure the cylindrical work piece 102 is acted upon by the 55 cutter 103 in which the grooves 104 extend radially.

60 To further illustrate the method of finishing a cylindrical surface, reference should be made to Figure 20. In this case, a relatively wide cutter 105 is used for finishing the cylindrical bearing surface 106. The axis 107 of the cutter is crossed with respect to the axis 108 of the work piece. Instead of moving the cutter in the direction of its axis to spread the finishing action over the surface of the work, it may 65 be moved in some other direction as indicated by the arrow 109. Thus it will appear that the axis 107 of the cutter will move from the position 109a to the position 109b. The points where 70 the two axes cross, thus progressively spread across the face of the cylindrical work piece as will be evident by the letters a, b, c, d and e. This action can either be the translation of a straight-faced cutter as illustrated in Figure 20, or a dish-type cutter as illustrated in Figures 10 and 11.

In either case, the shaving action is transferred along the surface to be finished so as to spread the cutting action uniformly.

What I claim as my invention is:

1. A machine for finishing a work piece having a surface of revolution comprising a frame, heads on said frame for mounting said work piece, a motor for rotating said work piece, ways on said frame, a tool carriage on said frame guided by said ways toward and away from said work piece, a motor on said carriage, means for supporting a tool on said carriage, connections between said tool and said last mentioned motor for driving said tool from said motor independently of said work piece, a third motor on said frame, and means driven by said third motor for feeding said carriage a predetermined distance toward said work piece and return.

2. A machine for finishing a work piece having a surface of revolution comprising a frame, 20 heads on said frame for mounting said work piece, a motor for rotating said work piece, ways on said frame, a tool carriage on said frame guided by said ways toward and away from said work piece, a motor on said carriage, means for supporting a tool on said carriage, connections between said tool and said last mentioned motor for driving said tool from said motor independently of said work piece, a third motor on said frame, means driven by said third motor for feeding said carriage a predetermined distance toward said work piece and return, and means for stopping said motors upon completion of said return stroke.

3. A machine for finishing a work piece having a surface of revolution comprising means for rotating said work piece, means for mounting a rotary tool having a working surface adapted to engage said surface of revolution in line contact, means for rotating said tool independently of said work piece, and means for feeding said tool toward said work piece along a path having a component perpendicular to said line of contact and a component parallel to said line.

4. A machine for finishing a work piece having a surface of revolution comprising a frame, means on said frame for mounting said work piece, means for rotating said work piece, ways on said frame, a tool carriage on said frame guided in said ways, means on said carriage for supporting a rotary tool with its working surface positioned to engage said surface of revolution in line contact, means for rotating said tool, and means for feeding said carriage a predetermined distance toward said work piece, said ways forming an oblique angle with said line of contact.

5. A machine for finishing a work piece having a surface of revolution comprising a frame, 60 a work support on said frame, a motor on said frame for rotating said work support, a tool carriage mounted on said frame for movement toward and from said work support, a tool support on said carriage, means for rotating said tool support, and feeding means for said carriage comprising means for moving said carriage toward said work support at feeding speeds, said last means responsive to feeding motion to reduce the rate of feeding movement near depth to finish said work piece with fine cuts.

6. A machine for finishing a work piece having a surface of revolution comprising a frame, a work support on said frame, a motor on said frame for rotating said work support, a tool car-

riage mounted on said frame for movement toward and from said work support, a tool support on said carriage, means for rotating said tool support, and feeding means for said carriage comprising cam-controlled toggle means for moving said carriage toward said work support at feeding speeds and reducing the rate of feeding movement near depth to finish said work piece with fine cuts.

7. A milling machine comprising a work support, a pair of tool carriages independently mounted for traverse toward and from said work support; toggles for each tool carriage, each comprising a link pivoted to a carriage, and a second link pivoted at one end to said first link and mounted for rotation about a fixed point on said machine, and means for simultaneously swinging said second link about their fixed pivots to traverse said carriages.

8. A milling machine comprising a work support, a pair of tool carriages independently mounted for traverse toward and from said work support; toggles for each tool carriage, each comprising a link pivoted to a carriage, and a second link pivoted at one end to said first link and mounted for rotation about a fixed point on said machine, and means for simultaneously swinging said second link about their fixed pivots to traverse said carriages, said last named means comprising a cam, a lever movable by said cam, and a link movable by said lever and connected to both of said second mentioned links.

9. A milling machine comprising a work support, a tool carriage movable obliquely toward and from said work support, a tool support on said carriage, a toggle comprising a pair of links movable to aligned position to feed said carriage to depth, to decrease the rate of feed near depth.

10. A milling machine comprising a work support, a tool carriage movable obliquely toward and from said work support, a tool support adjustably mounted on said carriage, a toggle comprising a pair of links movable to aligned position to feed said carriage to depth, to decrease the rate of feed near depth.

11. In a machine for finishing surfaces of revolution on a work piece utilizing a tool of frusto-conical form having cutting edges helically arranged on the peripheral surface thereof, the combination of means for rotating said work piece and said tool in contact with their axes in the same plane and angularly related so that said tool contacts said surface in substantially line contact, and means relatively feeding said tool and work piece along a path oblique to the line of contact to cut said surface to depth.

12. A machine for finishing a rotary work piece having contiguous angularly related surfaces of

revolution comprising means for rotating said work piece, a frusto-conical tool in line-contact with one of said surfaces, said tool having cutting edges inclined to the direction of rotation such that each edge initiates its cut near the intersection of said surfaces to throw chips away from said intersection, and means for rotating said tools.

13. A machine for finishing a work piece having a surface of revolution non-parallel to its axis comprising means for rotating said work piece at a speed above feeding speed, a frusto-conical cutter having cutting edges on its peripheral surface, means for supporting said cutter in line contact with said surface so that the end of said cutter adjacent its large diameter contacts the portion of said surface closest to the axis of said work piece, and means for rotating said cutter.

14. A machine for finishing a rotary work piece having contiguous angularly related surfaces of revolution comprising means for rotating said work piece, a rotary tool in line contact with one of said surfaces, said tool having cutting edges inclined to the direction of rotation such that each edge initiates its cut near the intersection of said surfaces to throw chips away from said intersection, and means for rotating said tool.

15. A machine for finishing a work piece having a surface of revolution comprising a frame, a work support on said frame, a motor on said frame for rotating said work support, a tool carriage mounted on said frame for movement toward and from said work support, a tool support on said carriage, means for rotating said tool support, and feeding means for said carriage comprising means for moving said carriage toward said work support in plunge cutting relation, said last named means including a cam formed to cooperate with said tool carriage to reduce the rate of feed near depth to finish said work piece with fine cuts.

16. A machine for finishing a work piece having a surface of revolution comprising a frame, a work support on said frame, a motor on said frame for rotating said work support, a tool carriage mounted on said frame for movement toward and from said work support, a tool support on said carriage, means for rotating said tool support, and feeding means for said carriage comprising means for moving said carriage toward said work support in plunge cutting relation, said last named means including a cam formed to cooperate with said tool carriage to reduce the rate of feed near depth to finish said work piece with fine cuts, to provide a substantial dwell at depth, and to return said carriage to non-cutting position.

ROBERT S. DRUMMOND.
